UNITED STATES PATENT OFFICE

JAY C. HOFFMAN, OF AKRON, OHIO

RAILWAY SIGNALING SYSTEM

Application filed April 7, 1930. Serial No. 442,100.

My invention relates to railway signaling systems, especially an automatic electric block-signal system using direct current and a normally closed track circuit. In such systems the automatic operation of the track circuit in each block is effected by changes in weather conditions or the seasons, and a customary practice is to have inspectors and repairmen adjust the current flow in the track circuits prior to wet and dry weather seasons so that the system may function effectively during each season. Thus during wet weather periods a considerable amount of electric current leaks from rail to rail through the wet ballast and cross ties, and a greater amount of energy or current is required at this time to operate the track circuit than in dry weather. Accordingly, the current flow in the track circuit must be regulated, otherwise under one condition the track relays become less sensitive in response to a train shunt, and under another condition there is danger of the relay remaining energized and producing a false signal indication. However, manual supervision and regulation has its objections and limitations, and my object in general is to provide automatic means for regulating the current flow in the track circuits so that the system will operate efficiently and safely at all times under all weather conditions. In carrying out my object I provide means which will automatically cut in a resistance in series with a normally-closed track circuit when the current flow therein reaches a predetermined value, thereby maintaining or increasing the sensitiveness of the circuit to a train or car shunt. A higher degree of broken rail protection is also thereby provided, and the electrical energy consumption in the track circuit is considerably reduced compared with prior practices. Preferably, I employ a self-regulating relay which includes a pair of magnet coils and an auxiliary armature, and interpose the desired resistance between the magnet coils in this relay. In action, the resistance will be cut in automatically in series, with the magnet coils when the energy applied reaches a value which will not cause the magnets to be over-

charged. Also the additional resistance placed in series with the magnet coils makes the relay exceptionally sensitive and will de-energize it instantly when the track circuit is occupied by a train, a very essential feature on railroads operating trains at a high rate of speed. 55

In the accompanying drawings, Figs. 1 and 2 are side and front elevations, respectively, partly in section, of a relay constructed to carry out my conception, and invention. Figs. 3 and 4 and 5 are diagrams of a section or block of a railway signaling system having such a relay in circuit therewith, and showing the operation thereof under different conditions. 65

The relay —A— shown in Figs. 1 and 2 is in some respects similar to the relays ordinarily used for the same purpose in that it embodies a pair of magnet windings or coils 2 and 3, and a pair of pole pieces 4 and 5, respectively, mounted on a suitable box or base 6 carrying any desired or required number of binding posts 7 to permit the device to be connected electrically to a railway signaling system. The relay also includes a main armature 8 hinged opposite the ends of the pole pieces, which armature carries one or more circuit make and break devices, such as an arm 9 having a spring contact member 10 adapted to make and break contact with a pair of terminal members 11 and 12, respectively, connected to a pair of the binding posts. 75

Now the features which distinguish relay *A* from others known to me reside mainly in the coupling of a resistance element or coil B in series with the magnet coils 2 and 3, respectively, either one or both of them, and in the use of an auxiliary armature C adjacent the pole pieces 4 and 5, respectively, together with a suitable circuit make and break device D operated by the auxiliary armature, whereby when the current flow through the magnet coils reaches a predetermined amount or value, the auxiliary armature will be attracted and the resistance element B will be cut in or placed in circuit in series with either one or both of the magnet coils of the relay. 95 100

As shown, the auxiliary armature C is pivotally supported upon a bracket 14 at one side of the pole pieces 4 and 5 but with a larger air gap or at a greater distance therefrom than main armature 8. Accordingly, the main armature will be attracted initially when current flows through the magnet coils, and a small amount of current will hold the main armature attracted, whereas the auxiliary armature will not function until a predetermined higher amount of current flows through the relay magnet coils. The auxiliary armature can also be set or adjusted by a set screw 15, and by a change in tension 10 of its controlling spring 16, to cause it to operate at any point within the range of the energy or current flow commonly used in a normally-closed railway signaling track circuit, represented in Figs. 3 to 5, by a section 15 or block of tracks E having a source of electric current such as a battery F connected therewith, including an adjustable resistance G.

The make and break device D is shown in Fig. 1 as comprising a contact spring 17 normally engaged with a fixed contact blade 18 and adapted to be raised apart therefrom by an arm 19 extending from armature C when this armature is attracted by the pole pieces. 25 An adjustable weight 20 may also be connected to arm 19 to control the action of auxiliary armature C. The contact member 17 and piece 18 are connected to binding screws 22-22' which are attached to upright 30 supporting conductors 23-23' for the resistance element or unit B, and this resistance unit is connected in series with the magnet coils 2 and 3 of the relay but shunted or cut out from the track circuit E when the switch 35 contacts 17 and 18 are engaged.

Track circuit E is a normally-closed circuit, and self-regulating relay A is connected therein at one end of the section or block of tracks as customarily, while the battery F 45 and adjustable resistance G are connected to the opposite end of the tracks in the same section or block. In practice, the adjustable resistance G is set to permit a minimum amount of current to flow from the battery 50 to maintain the track circuit and to attract and hold main armature 8 when the ballast and cross ties are wet, but without operating the auxiliary armature. Accordingly, resistance B is cut out at this time, or when the 55 current losses are at maximum. Regulation or due allowance having been made for current losses, the track circuit is then adapted to function with a considerable degree of safety during wet weather periods. However, when wet weather conditions are succeeded by a dry or cold period, and no such 60 losses of current occur, the relay magnet coils become overcharged with current to such an extent that the relay is less sensitive or responsive to a train shunt, and the train shunt 65

or short-circuiting of the track circuit by the car wheels is also less effective or not as easily effected in dry weather. Thus when the relay is overcharged there is a much smaller margin of safety in dry or cold weather and more danger or risk that a false signal will be given. 70

The automatic regulating relay —A—, increases the margin of safety in such track circuits as it corrects or compensates for the differences in current flow in the track circuit under the varying conditions which prevail, and permits the track circuit to perform equally as well in dry or cold weather as in wet weather. Thus, in wet weather the auxiliary armature is normally released which cuts out the resistance C as shown in Fig. 4 to permit the relay to function sensitively with a minimum amount of current at a time when leakage and losses in current are more prevalent. In dry weather when leakage is less or no loss of current occurs the auxiliary armature is attracted to place the resistance B in series with the relay coils as shown in Fig. 3, whereby the relay is prevented from overcharging and again maintained in a sensitive and responsive state to a train shunt or short circuit. Fig. 5 shows a wheeled truck or car H in the track block and in this case the track circuit is short-circuited and relay A is completely de-energized to produce a signal over any suitable signaling circuit or circuits J. The signaling circuit is only shown in part, inasmuch as such circuits are well known and used in many ways, singly or in multiple. 85

In operating a track circuit embodying the present invention the electrical energy or current consumed is considerably reduced as compared with general practices; the relay 105 functions with increased sensitivity and responsiveness; the margin of safety is increased; the relay operates reliably under a train shunt produced by either light or heavy railway traveling equipment; and frequent periodical resistance adjustments in the battery current supply may be avoided. 110

What I claim is:

1. In a railway signaling system, a normally closed track circuit having a source of current supply, a signaling circuit, a relay in said track circuit, a main armature, for said relay controlling said signaling circuit, and an auxiliary armature for said relay operated by the current flowing through said track circuit and dimensioned to be actuated under different current values than said main armature for producing additional resistance in said track circuit automatically when the current values exceed a predetermined setting. 115

2. In a railway signaling system, a normally-closed track circuit, a source of electric current, means for regulating the amount of current supplied to said circuit, a signaling 130

- circuit, a relay in said track circuit for controlling said signaling circuit, a resistance in series with said relay, and automatic means controlled by said relay for short-circuiting
- 5 said resistance under predetermined settings of said current regulating means.
3. In a railway signaling system, a circuit containing a relay and resistance in series; said relay having a main armature and
- 10 switching devices for controlling a signaling circuit, and an auxiliary armature and switching means for short-circuiting said resistance.
4. In a railway signaling system, a normally-closed track circuit, means for regulating the amount of electric current for said circuit, a signal controlling relay connected with said circuit, and automatic means controlled by said relay for maintaining said
- 15 20 relay sensitively responsive to a train shunt in said circuit under changes in potential induced by different weather conditions.
5. In a railway signaling system, a circuit, a relay having a pair of magnet coils connected in said circuit, a resistance element, and means for cutting in said resistance element in series and between said magnet coils when the electric energy applied to same exceeds a predetermined value.
- 25 30 6. In a railway signaling system, a direct current relay having an armature, magnet coils and a resistance element adapted to be connected in series relation, and make and break devices operatively controlled by said armature for placing said coils and resistance element in series relation when the electric energy flowing through said coils reaches a predetermined value.
- 35 7. In a railway signaling system, a relay having a main armature, and means for making and breaking a signaling circuit, including an auxiliary armature less responsive than said main armature, magnet coils and a resistance element adapted to be connected
- 40 45 in an electric circuit, and means operatively controlled by the movement of said auxiliary armature for cutting said resistance element in and out of said circuit.

In testimony whereof I affix my signature.

50 JAY C. HOFFMAN.
